UNITED STATES PATENT OFFICE.

VIRGIL D. PORTER, OF WYLM, ALABAMA, ASSIGNOR OF ONE-HALF TO WM. H. BENNETT, OF BIRMINGHAM, ALABAMA.

DUPLEX COOKING ATTACHMENT FOR STOVES.

Application filed November 10, 1924. Serial No. 748,841.

To all whom it may concern:

Be it known that I, VIRGIL DE VOT PORTER, a citizen of the United States of America, residing at Wylam, in the county 5 of Jefferson and State of Alabama, have invented certain new and useful Improvements in Duplex Cooking Attachments for Stoves, of which the following is a specification.

10 My invention relates to a duplex cooking attachment for liquid and gaseous burning stoves, and has for its object to utilize one burner to heat two vessels for cooking therein.

15 My invention contemplates the provision of a flanged cooking vessel support adapted to set on the stove top with its flange at one end adapted to nearly surround the burner that is lighted and to direct the products 20 of combustion from the burner laterally through a duct to a spider adapted to receive the second vessel to be heated, such spider being designed so as to permit the free escape of the products of combustion 25 while causing them to pass crosswise of the bottom of the second vessel and thus to heat the latter most efficiently.

My invention also contemplates tapering the duct to concentrate the heat under the 30 center of the spider.

My invention further comprises the novel details of construction and arrangements of parts, which in their preferred embodiment only are illustrated in the accompanying 35 drawings which form a part of this specification, and in which:

Fig. 1 is a plan view of a part of a stove showing my attachment in plan with the vessel illustrated in full lines and the second 40 vessel in dotted lines.

Fig. 2 is a side elevation of the attachment.

Figs. 3 and 4 are cross-sections taken respectively on the lines 3—3 and 4—4 of 45 Fig. 1.

Similar reference numerals refer to similar parts throughout the drawings.

In the embodiment of my invention illustrated in the drawings, I show a typical 50 gas stove top 1 having a burner 2 and I mount my attachment on the top with its marginal flange 3 at one end surrounding the space above the burner 2 except on one side where the flange merges into the convergent side walls 4 of the heat duct, which

walls 4 in turn merge into the curved flange 5 of the spider support for the secondary cooking vessel 6. The flange 3 is formed with a wide horizontal top flange 7 which forms a complete eye adapted to receive and be closed by the primary cooking vessel 8. At one side this flange merges flush into the top 9 of the lateral heat duct through which the products of combustion flow between the side walls 4 to the spider support for the secondary cooking vessel. This spider support comprises a series of straight divergent ribs 10 which extend from where they join the top wall 9 of the duct across the vessel support and at their outer ends are 60 connected to the flange 5. The ribs rise above the level of the top 9 and the flange 5 and depend substantially below the under surface level of the top 9. This thus forms a raised spider support which will permit 65 the products of combustion passing through the duct to flow transversely across under the secondary vessel and freely escape on all sides about it so that regardless of the size of such vessel it is not possible for it to choke and put out the burner 2. The convergent side walls 4 of the heat duct concentrate the heat towards the center of the spider and the ribs tend to carry it across 70 under the vessel.

In operation, the primary cooking vessel 8 should be of such size as to close the eye above the burner and cause all of the products of combustion to be diverted laterally through the tapering duct to the divergent 75 channels between the spider ribs that support the secondary cooking vessel and thus the heat from one burner can be most efficiently used for cooking in two vessels.

Though I have described with great particularity the details of the embodiment of the invention herein shown, it is not to be construed that I am limited thereto, as changes in arrangement and substitution of equivalents may be made by those skilled in 80 the art without departing from the invention as defined in the appended claims.

Having thus described my invention, what I claim as new and desire to secure by Letters Patent, is:—

1. An attachment for gas and oil burning stoves, comprising a shallow marginal flanged casting having two eyes adapted to be disposed above two adjacent stove burners, the eye over one burner being un- 110

obstructed and adapted to be closed by a cooking vessel, the eye over the other burner having integral divergent shallow cast ribs extending transversely from side to side 5 thereof and having their upper edges lying in a plane raised slightly above the top level of the casting, the ribs providing uninterrupted heat channels which diverge from the line of approach of the products 10 of combustion flowing between the side flanges of the casting from the closed to the ribbed eye.

2. An attachment for gas and oil burning

stoves according to claim 1, in which the side flanges of the casting are drawn together to contract the passage between the eyes symmetrically and said ribs are arranged to divide the products of combustion delivered to them from the contracted throat of said passage into substantially 15 20 equal parts.

In testimony whereof I affix my signature.

VIRGIL D. PORTER.
